UNITED STATES PATENT OFFICE.

HARRY RANDOLPH VAN DEVENTER, OF SUMTER, SOUTH CAROLINA, ASSIGNOR, BY
MESNE ASSIGNMENTS, TO SPLITDORF ELECTRICAL COMPANY, OF NEWARK, NEW
JERSEY, A CORPORATION OF NEW JERSEY.

MAGNETO ATTACHMENT.

1,211,507.

Specification of Letters Patent. Patented Jan. 9, 1917.

Application filed September 22, 1914. Serial No. 863,028.

To all whom it may concern:

Be it known that I, HARRY RANDOLPH VAN DEVENTER, a citizen of the United States, residing at Sumter, in the county of Sumter and State of South Carolina, have invented certain new and useful Improvements in Magneto Attachments, of which the following is a specification, reference being had to the accompanying drawing.

My invention relates to attachments for magnetos and has for its object, the provision of spring arms which will be neat in appearance, strong, durable and cheap to manufacture, and which may be easily and cheaply attached to a magneto of the rotary type, thereby permitting same to be equipped with actuating springs to operate as an oscillator.

Another object is to provide a spring arm for magnetos, made from stamped and formed sheet metal.

A further object is to provide an oscillating magneto of few parts and one in which the spring arms also serve to clamp the magnets and top plate of the machine in place.

My invention may be used in connection with any magneto having a projecting shaft which shaft may be connected to a shuttle wound armature or to any movable part, whereby the machine is operated.

Figure 1 is a view in perspective, illustrating my invention in use on a magneto. Fig. 2, a view of the formed spring arm constituting the invention.

Like figures denote the same parts wherever they are shown.

1 denotes a magneto, the shaft of which is shown at 2. Mounted upon this shaft is the trip lever 3, to which is connected the springs 4 and 5. The outer ends of these springs are carried on suitable pins, shown at 6 and 6', which are fastened in the ends 7 and 7' of the spring arms 8 and 8'. These arms are clamped to the sides of the magneto by means of screws, one of which is shown at 9, passing through or between the magnets of the magneto, and entering the pole pieces of same.

It will be noted that the magneto may have a suitable framework of any well known type, this usually consisting of the base on which the magneto rests, to which

is attached pole pieces (not shown). Across the top of these pole pieces is the top plate 15. The top plate, base, and pole pieces, comprise the framework of the magneto adapted to support the magnets, and to which the spring arms 8 and 8' are attached as just described. As the construction of such a framework is readily understood I do not describe the same in detail.

The spring arms 8 and 8' have projecting lugs 10 and 10', which fit over the top plate 15 of the magneto and hold same in place. A corresponding but shorter projecting portion 13 serves to locate each arm vertically, in relation to the opening 14 between the magnets.

Fig. 2 shows an alternate form of construction of the spring arms whereby the posts 6 and 6' for supporting the springs are eliminated, their place being taken by the outwardly turned ends 11 formed integral with the spring arm, and provided with groove 11' for supporting the spring.

From the foregoing it will be seen that the spring arms 8 and 8' not only support the springs connected to the armature trip lever, but also clamp the top plate in place, and also clamp the magnets to the pole pieces. It is also evident that these spring arms may be attached to an ordinary rotary magneto, thereby making same an oscillator without removing the armature, or in any other way disturbing the assembly of the parts, these arms being in the nature of an attachment. This is a great saving to those using both the rotary and oscillating types of magnetos, as they are not obliged to stock two kinds of magnetos as would otherwise be the case.

I am aware that magnetos with spring arms are in common use, but such arrangements have the spring arms as part of the end plate 12 of the magneto; or where the arms are attached to the sides of the magneto they are bolted to the edges of the end plates, and in no case do these arms form an attachment for a rotary magneto arranged to be put on same at any time after its construction and use as a rotary machine. Nor do the arms on any such machines serve to hold on the top plate of same, thereby eliminating screws or other devices for this purpose, nor do they serve to clamp the magnets to the pole pieces of the magneto.

Having thus described my invention, I claim:

1. In combination with an ignition generator having a rotor shaft, a trip lever, a spring support secured to the generator and formed from a sheet of metal having a side portion adapted to be clamped to said generator and supported wholly thereby, lugs on said support adapted to position the same on said generator, an arm portion on said support at right angles to the side thereof, spring supporting means carried by said arm portion, and a spring between said trip lever and said spring supporting means.
2. In combination with an ignition generator having a rotor shaft, a trip lever, a spring support secured to the generator and formed from a sheet of metal having a side portion adapted to be clamped to said generator and supported wholly thereby, lugs on said support adapted to position the same on said generator, an arm portion on said support at right angles to the side thereof, a spring support carried by said arm portion and integral therewith, and a spring between said trip lever and said spring supporting means.
3. In combination with an ignition generator having a rotor shaft, a trip lever, a spring support secured to the generator and formed from a sheet metal blank having an apertured portion adapted to be clamped to said generator and supported wholly thereby, means on said spring support adapted to position the same on the generator, an arm portion on said support at right angles to the side thereof, a spring support on said arm portion, and a spring between said trip lever and said spring supporting means.
4. In combination with an ignition generator having a rotor shaft, a trip lever, a spring support having an apertured portion adapted to be clamped to said generator and supported wholly thereby, lugs on said support adapted to position the same on said generator, an arm portion on said support at right angles to the apertured part thereof, and a spring support carried by said arm portion and integral therewith.
5. In combination with an ignition generator having a rotor shaft, a trip lever, a

spring support having an apertured portion adapted to be clamped to said generator and supported wholly thereby, lugs for positioning said apertured portion, an arm support at right angles to said apertured portion, and a spring support secured to said last portion, substantially as described.

6. In combination with an ignition generator having a rotor shaft, a trip lever, a spring support secured to the generator having an apertured portion adapted to be clamped thereon and supported wholly thereby, means on said apertured portion adapted to position the same on said generator, an arm portion at right angles to the apertured portion of said spring support and integral therewith, and a spring between said arm portion and said trip lever.

7. The combination with a magneto of brackets secured to the pole pieces thereof and supported wholly thereby, portions of said brackets forming magnet clamps, portions of said brackets extending at right angles to the pole pieces of the magneto, and spring supports on said latter portions.

8. The combination with a magneto of a member clamped to the side thereof said member comprising a magnet clamp a top plate clamp and a spring support, substantially as described.

9. The combination with a magneto having a top plate of a member adapted to be clamped to the side of the magneto, a lug on said member overlapping the said top plate of said magneto, an arm at right angles to the clamp side of said member, and a spring support on said arm, substantially as described.

10. In combination framework, two magnets, a pair of brackets attached to said framework and clamping said magnets to said framework, arms on said brackets at right angles to the clamping surfaces thereof, lugs on said brackets projecting between said magnets and spring supports on said arms.

In testimony whereof I hereunto affix my signature in the presence of two witnesses.

HARRY RANDOLPH VAN DEVENTER.
